UNITED STATES PATENT OFFICE.

MONROE S. HOWARD, OF WAUKON, IOWA.

AUTOMATIC EXPRESSION CONTROL FOR MECHANICALLY-OPERATED PIANOS.

1,132,584.

Specification of Letters Patent. Patented Mar. 23, 1915.

Application filed October 4, 1913. Serial No. 793,348.

To all whom it may concern:

Be it known that I, MONROE S. HOWARD, a citizen of the United States, residing at Waukon, in the county of Allamakee and State of Iowa, have invented certain new and useful Improvements in Automatic Expression Control for Mechanically-Operated Pianos; and I do hereby declare the following to be a full, clear, and exact description of the invention, such as will enable others skilled in the art to which it appertains to make and use the same.

In music, expression is obtained by variations in time and loudness and in piano playing peculiar tones are obtained by variations in the touch of the player. In all music certain notes should be accented, for instance, a primary accent of the first note of every measure, and in certain kinds of time, such as 2-4 and 6-8, there is also a secondary accent to each measure which is less pronounced than the primary accent, and these accents are varied more or less and other notes are accented to properly bring out the phrasing of a composition. It is also desirable at times to give prominence to different notes in chords. Thus all the finer tones of expression are only obtainable by the individual control of the notes, as distinguished from the general tones obtained by varying the loudness or the time.

In all forms of mechanically operated piano players provision is made for varying the tone quality and time, affecting the whole range of the instrument simultaneously, and in some players it is possible to vary the loudness of either the treble or the bass separately. Many attempts have been made to secure some degree of individual control, but to my knowledge, none has accomplished what I have.

My object is to produce a mechanism whereby not only varying degrees of accent can be produced as desired, but different notes can be struck with varying degrees of loudness at the same time, and different qualities of human touch can be imitated so that a pianist's rendition of a composition may be accurately reproduced. I obtain this effect by certain variations of the shape of the advance ends of the perforations in the music roll, or the width of the opening, or both, and in the mechanism including a tracker bar having two or more openings for each note the openings to be used separately or in combination.

In the drawings wherein is shown an embodiment of my invention, Figure 1 represents a vertical transverse sectional view through that much of an automatic piano player required to illustrate my invention, Fig. 2 represents a fragmental view in front elevation of a tracker bar and the music sheet, Fig. 3 represents a sectional view on the line 3-3 of Fig. 1, Fig. 4 represents a sectional view on the line 4-4 of Fig. 1, Fig. 5 represents a sectional view on the line 5-5 of Fig. 1, Fig. 6 represents a sectional view on the line 6-6 of Fig. 1, Fig. 7 represents a modification of the construction of the secondary exhaust or tension chamber and striker pneumatic, Figs. 8 and 9 represent detail sectional views of modifications of valve structures adapted for operation in connection with the form of invention illustrated in Fig. 7, Fig. 10 represents a transverse vertical sectional view of a modified form of primary exhaust or tension chamber, Fig. 11 represents a sectional view similar to Fig. 1, but showing a modified construction of the device, Fig. 12 represents a fragmental view in front elevation of the tracker bar and music sheet employed in connection with mechanism illustrated in Fig. 11, Fig. 13 represents a modification of the invention as disclosed in Fig. 11, Fig. 14 represents a transverse vertical sectional view through the secondary tension chamber and striking pneumatic in a modified form, Fig. 14^a represents a central sectional view through the valve shown in Fig. 14, Fig. 15 represents a further modified form of the device, Fig. 16 represents another modification of the tracker bar and music sheet, Fig. 17 represents a vertical sectional view through one of the valve actuating bellows, showing means for limiting the movement of the bellows and valve connected therewith, and, Fig. 18 represents a front elevation of a modified form of tracker bar and music sheet adapted for use in connection with the mechanism shown in Fig. 1.

Referring to the drawings in detail, 20 indicates one of a set of striking pneumatics which is divided into any desired number of compartments 21. Each of the compartments 21 is connected by a passage 22 with an apertured cylinder 23, through which works a plunger 24 mounted upon a rod 25.

As clearly shown in Fig. 6, each of the 110 passages 22 communicates by a set of openings 26^a in the wall of the cylinder 23 with

the interior of the latter. Each set of openings 26^a is disposed in a different vertical plane, and the ends of the cylinder 23 are open to permit air to circulate therethrough.

5 As the piston 24 rises it cuts off connection successively between the compartments of the pneumatic 20 and the external air admitted through the top of the cylinder 23, and at the same time establishes connection 10 between them and the secondary exhaust or tension chamber 26. A bellows pneumatic 27 having connection with the rod 25 is located in the chamber 26 and is divided into compartments corresponding in number to 15 those in the striker pneumatic 20. Each of the compartments within the bellows pneumatic 27 is connected by a passage 28 with a second valve in the primary exhaust or tension chamber 29. The valve last referred 20 to is substantially identical in construction to the valve first described comprising the cylinder 23, plunger 24, and is also provided with a plunger 30 secured on a rod 31 adapted to work over a series of openings 25 formed in the casing 32 communicating with the passages 28, whereby when said plunger is raised communication is established between the primary tension chamber 29 and the compartments of the bellows pneumatic 30 27 successively through the passages 28. A primary bellows pneumatic 33 is located within the primary tension chamber 29 and is suitably connected with the rod 31 for actuating the plunger 30 when said bellows 35 is actuated. The bellows 33 is also constructed with a plurality of compartments, each of which communicates by the passage 34 and tube 35 with one of a set of openings 36 formed in the tracker bar 37. Each set 40 of openings 36 is arranged on a line substantially transverse to said tracker bar.

45 Springs 38 are provided in each of the chambers 26 and 29 for compressing or collapsing the bellows pneumatic therein. The tubes 35 and passages 34 are connected by small bleed holes (not shown) with the primary exhaust chamber 29 so that, when the openings 36 in the tracker bar are covered by the solid portions of the music sheet, air 50 is exhausted from these tubes and passages to the same pressure as exists in the chamber, and the primary pneumatic 33 is compressed by its spring 38.

55 The movement of the pneumatic 33 raises the plunger 30 and uncovers the openings in the cylinder 32. Thus the compartments of the secondary pneumatic 27 communicate with the primary exhaust chamber 29 by the passages 28, and the secondary pneumatic 27 is collapsed by its spring 38.

60 When the openings 36 in the tracker bar 37 are uncovered by the elongated and angular perforations 38^a in the music sheet 39 the exterior air is admitted, the pressure of 65 which being higher than that in the exhaust chamber causes the primary pneumatic 33 to expand. If the angle of the advance ends of the perforations 38^a is the same as that at which the openings 36 in the tracker bar 37 are disposed, all the openings will be uncovered simultaneously, thus inflating all the compartments of the primary pneumatic 33, which latter moves the plunger 30 to the bottom of the cylinder 32 and permitting air to enter through the top of said cylinder 70 and to pass downwardly through the passages 28 and inflate the secondary pneumatic 27. The movement of the pneumatic 27 is imparted to the plunger 24 and the latter moved upwardly within the cylinder 23, thus connecting all of the compartments of the striking pneumatic 20 with the exhaust chamber 26 practically simultaneously and giving a quick hard stroke to the piano hammer through the connections 40 and 41. 75 If the advance end of the perforation is given an angular or partially angular cut, the openings 26^a will be uncovered in succession more or less rapidly and the compartments of the striking pneumatic 20 will be collapsed at a corresponding rate, giving any desired force to the stroke. One or more of the compartments of the striking pneumatic may be collapsed in advance so that a short stroke would be used in striking 80 the note and soft tones obtained in that way.

85 The mechanism above described may be provided and operated with a tracker bar and music sheet of the construction shown in Fig. 18. In this type the openings in the 90 tracker bar are arranged in sets or groups, each set corresponding in number to the number of compartments in the striking, primary and secondary pneumatics. The openings in this tracker bar are aligned longitudinally of the latter and the openings of each set are adapted to be uncovered simultaneously or successively according to the shape of the advance ends of the perforations in the music sheet. A modification of 95 this form of my invention is obtainable by substituting the secondary exhaust chamber 42, striking pneumatic 43, and coöperating devices shown in Fig. 7 for the corresponding parts of the device as shown in Fig. 1. 100 In this form, the striking pneumatic 43 is provided with but one compartment communicating with a cylinder 44 by the passages 45. An apertured seat 46 is provided in the bottom of the cylinder 44 and receives a hollow valve 47 having an imperforate head 48 and slot 49. The hollow valve 47 is connected with the secondary pneumatic 42^a, whereby when one or more of the compartments of the latter are inflated, said 105 valve will be moved upwardly a greater or less distance, depending upon the number of compartments of said pneumatic which are inflated. In this way the strength of the 110 stroke of the piano hammer is controlled by 115

120

125

130

restricting the flow of air between the striking pneumatic 43 and the exhaust chamber 42 by governing the length of opening of the slot 49, depending upon the number of compartments of the pneumatic 42^a which are inflated to raise the hollow valve 47.

Figs. 8 and 9 show modifications of the valve for restricting the flow of air between the striking pneumatic 43 and exhaust chamber 42 of the form of my invention shown in Fig. 7. In Fig. 8 the valve 50 is provided with a tapering stem 51 suitably connected with the pneumatic 42^a and adapted to be raised so as to permit air to flow in desired volume from between exhaust chamber and the striking pneumatic. In Fig. 9 the cylinder 44 is provided with a downwardly extending slot 52 communicating with the passage 45 and adapted to be covered and uncovered to establish and interrupt communication between the exhaust chamber and striking pneumatic by the plunger 53.

Fig. 10 shows a slightly different arrangement of the primary exhaust chamber 29 and its coöperating accessories. In this form the cylinder 32 is located in the bottom of the chamber 29 and the rod 31 actuating the plunger 30 is provided on its upper end with a balancing piston 54 working in a cylinder 55.

In the construction of my expression control for piano players shown in Fig. 11, any desired form of valve system and striking pneumatics may be used, and the control of the latter is effected by connecting the striking pneumatic and connections 55^a with a secondary or restraining bellows 56 of suitable size and in such manner that the latter is caused to open as the striking pneumatic 57 collapses to strike a note. If air is admitted freely into the bellows 56, it is obvious that there will be practically no resistance to the striking pneumatic, but if the opening through which the bellows is supplied with air is more or less restricted, it will offer proportionately more or less resistance to the movement of the striking pneumatic and thus vary the stroke, as desired. In order to control the air in the bellows 56 and consequently the resistance to the striking pneumatic, I provide a suitable passage 58 and tube 59 connecting said bellows with the openings 60 in the tracker bar 61. The openings 60 are located above the openings 62 which are adapted to co-operate with the striking pneumatic and valve system and are preferably tapered longitudinally of the tracker bar. A bleed hole 63 is provided between the passage 58 and the exhaust chamber 64 so that the air in the bellows, passage 58 and tube 59 is exhausted to the same tension as the exhaust chamber when the opening 60 in the tracker bar is covered and the bellows offers a maximum

resistance to the striking pneumatic 57. By cutting perforations 65 in the music sheet 66 of suitable width so as to uncover more or less of the openings 60 before the striking mechanism is set in operation by uncovering the openings 62, the desired variations in the force of the strokes may be obtained. A suitable flap valve 67 is provided for permitting the air to escape from the bellows 56, when the latter closes.

Another form of tracker bar and music sheet for the device shown in Fig. 11 is shown in Fig. 16, wherein the music sheet 68 is provided with perforations 69 having the advance ends thereof suitably cut so as to cover or partially cover the elongated openings 70 in the tracker bar 71. In this form of tracker bar the openings 70 are connected by the tubes 59 and passage 58 with the controlling bellows 56.

Referring to Fig. 14, 26 denotes the secondary exhaust chamber of the form of my invention illustrated in Fig. 1, in which is located the secondary pneumatic 27 having passages 28 each communicating with a compartment of the pneumatic 27 and adapted to be selectively or simultaneously opened in a manner as set forth in the description of Fig. 1. The pneumatic 27 is connected with and adapted to actuate a hollow valve 72 adapted, when closed, to communicate the striking pneumatic 20 with the external air through the passage 73 and the opening 74 through the center of the valve. A second or controlling bellows 75 is provided and connected with the upper portion of the cylinder in which the valve 72 is seated through the passage 76. The valve 72 is provided with a tapered stem 77, working through an apertured disk 78 and adapted to control the passage of air to the bellows 75.

Instead of the bellows 56 and 75 shown in Figs. 11 and 14 for controlling the action of the striking pneumatics, I may employ an ordinary dash pot, as shown in Fig. 13 and suitably connect it at 79 with the striking pneumatic for controlling the action of the latter. In this instance, the tube 59 communicating with the auxiliary opening in the tracker bar is operatively connected through the bottom of the dash pot.

A combination of the various devices herein described is shown in Fig. 15, wherein the striking pneumatic 20, secondary exhaust chamber 26 and controlling valve therebetween are identical in construction to Fig. 1. A second or auxiliary bellows 80 of suitable size is mounted over the striking pneumatic 20 and is suitably connected with the latter by devices 81. A passage 82 and tube 83 connect the controlling bellows 80 with a suitable opening in the tracker bar which latter is adapted to be partially or entirely covered by the music roll, as before described, to control the passage of air to

the bellows 80. This form of my invention will give the most complete control of the touch or striker action.

In Fig. 17 I have shown means for limiting the movement of the compartments of the various bellows and consequently the movement of the valve connected therewith. In said figure, 84 indicates an extension provided on the end of the partition between 10 each compartment and 85 denotes a series of steps adapted to be successively engaged by the extensions 84, as the compartments of the bellows are successively inflated.

In all of the forms of my invention herein described perfect and independent control of the degree of loudness of each individual note in the range of the musical instrument is obtained automatically. It is therefore apparent that with proper shaping 20 of the note perforations the individual notes in a composition may be played with the exact relative degree of loudness and quality of touch to give the most pleasing effect.

25 What I claim as new is:

1. An automatic piano player comprising; a tracker bar, a plurality of striking pneumatics, said striking pneumatics having opposing chambers, tubular means connecting said tracker bar with one of said chambers, tubular means connecting said tracker bar with the opposing chamber, said last mentioned means regulating the striking force of said striking pneumatics, 35 means communicating between each of said tubular means to reduce the pressure in said tubular means to the same degree of force, and means positioned within said first tubular means adapted to regulatingly actuate said striking pneumatic against the resistance of said opposing chamber, said last mentioned communicating means consisting of a valve member having a tubular chamber, and a reciprocating piston reciprocating 40 within said tubular chamber having an increasing opening thereto.
2. An automatic piano player comprising; a tracker bar, having a plurality of groups

of apertures therethrough, a striking pneumatic having opposing chambers, one to actuate said striking pneumatic, and the other to determinately resist said actuation, means connecting one group of said apertures in said bar to said actuating chamber in said striking pneumatic, means connecting another group of apertures in said tracker bar to said opposing chamber, means communicating between said connecting means to equalize the pressure therebetween, and means positioned within one of said communicating means to determinately actuate said striking pneumatics, consisting of a valve casing communicating with said connecting means, and means operating within said valve casing to determinately and increasingly open said communication to said connecting means, said last mentioned means regulating the actuation of said striking pneumatic.

3. An automatic piano player comprising; 70 a plurality of compartmented striking pneumatics, said compartments opposing one another, means connecting each of said compartments to operate the same in unison, a tracker bar, communicating means between 75 said tracker bar and one of said compartments to actuate said striking pneumatics, a second communicating means between said tracker bar and the opposing compartments of said striking pneumatics to oppose the 80 actuation thereof, a tubular means having an increasingly actuated reciprocating member therein, positioned in one of said communicating means to regulate the degree of actuation of said striking pneumatics and 85 means between said communicating means to balance the pressure between said communicating means upon the actuation of said last mentioned means.

In testimony whereof I have signed my 90 name to this specification in the presence of two subscribing witnesses.

MONROE S. HOWARD.
